US00D726348S

(12) **United States Design Patent**
Cohen

(10) **Patent No.:** **US D726,348 S**
(45) **Date of Patent:** **** Apr. 7, 2015**

(54) **SELF-CONTAINED SOLAR-POWERED
SCREW-IN LED MODULE**

(71) Applicant: **RSR Sales, Inc.**, Ann Arbor, MI (US)

(72) Inventor: **Richard Cohen**, Ann Arbor, MI (US)

(73) Assignee: **RSR Sales, Inc.**, Ann Arbor, MI (US)

(**) Term: **14 Years**

(21) Appl. No.: **29/453,763**

(22) Filed: **May 2, 2013**

(51) LOC (10) Cl. **26-04**

(52) U.S. Cl.

USPC **D26/1**

(58) **Field of Classification Search**

USPC D26/1-4, 28-36; 313/313, 315, 316,
313/317, 318; 315/52, 53, 56, 57, 58
